Des. 225,094

Patented Nov. 14, 1972

225,094

SASH

Melvin Zakarin, 23 Ogden Lane,
Englishtown, N.J. 07726

Filed July 22, 1970, Ser. No. 24,059

Term of patent 3½ years

Int. Cl. D2—07

U.S. Cl. D2—385

FIG. 1.

FIG. 2.

FIG. 3.

FIG. 1 is a front isometric view of a sash showing my new design, the design of the belting continuing around the back.

FIG. 2 is a top plan view of the sash.

FIG. 3 is an inside front elevational view thereof, shown broken away for convenience of illustration.

I claim:

The ornamental design for a sash, substantially as shown and described.
